UNITED STATES PATENT OFFICE.

JEREMIAH CAMPBELL, OF CHELSEA, MASSACHUSETTS.

RECORDING-SCALE.

SPECIFICATION forming part of Letters Patent No. 627,978, dated July 4, 1899.

Application filed September 16, 1897. Serial No. 651,815. (No model.)

To all whom it may concern:

Be it known that I, JEREMIAH CAMPBELL, a citizen of the United States, residing at Chelsea, in the county of Suffolk and State of Massachusetts, have invented a new and useful Improvement in Recording-Scales, of which the following is a full, clear, and exact description, reference being had to the accompanying drawings, forming a part of this specification, in explaining its nature.

The invention is an improvement upon that described in my Letters Patent No. 544,207, dated August 6, 1895, and No. 558,630, dated April 21, 1896; and it relates especially to the coupling together of the counterpoise and the recording devices, whereby the movement of the counterpoise causes the movement of the recording devices, and whereby also the counterpoise may be used independently of the recording devices in weighing.

It also relates to means whereby the recording devices are centered in respect to the printing - type and counterpoise during the printing or recording operation.

It further relates to means for obtaining two recording-impressions by the use of one type-ribbon.

It also relates to means whereby a single lever controls the counterpoise-latch and the connection between the counterpoise and the recording devices.

In the drawings, Figure 1 is a view in side elevation of scales having the features of my invention. Fig. 2 is a view in side elevation, enlarged, of a portion of the scale-beam, the counterpoise, and the recording devices. Fig. 3 is a view in vertical section upon the dotted line 3 3 of Fig. 2. Fig. 4 is a view principally in vertical section, showing the connection between the counterpoise and the recording devices. Fig. 5 is a detail view in plan of the counterpoise. Fig. 6 is a view in vertical section upon the dotted line 5 5 of Fig. 5.

The scale preferably has the tare-beam A and tare-counterpoise A', the main scale-beam B and main counterpoise B', and the stationary track C below the main scale-beam, upon which are mounted to slide lengthwise the recording devices C'. The scale-beam B has the notched upper edge b and upon its lower edge the line of inverted numerals b', from which recording - impressions are taken, substan-

tially as described in my said Patent No. 558,630.

The counterpoise B' has a latch b² to engage the notches in the upper edge of the scale-beam and which is operated by the lever b³ upon the front side of the counterpoise. The latch is pivoted at b⁴ to the counterpoise and moved downward by the spring b⁵. It is lifted from engagement with the notch by the lifting-pin b⁶ on the lever-shaft b⁷. (See Fig. 6.) The counterpoise also has at its front end b⁸ the sight-point b⁹, which is in line with the latch. The counterpoise also carries a short bar or auxiliary scale-beam E, upon which a small counterpoise E' is adapted to be moved, this beam and counterpoise weighing smaller fractions or weights than the larger counterpoise. The short beam E is not notched, and the small counterpoise E' is moved back and forth thereon by a knob e'. It is centered in respect to the recording devices during the printing operation, as will hereinafter appear, and has a line E² of inverted numerals upon its under side which are in line with the numerals of the scale-beam.

The recording devices C' have the two parts or sections c'c', and the part c' is movable vertically upon the part c by a cam-lever c², as described in my said Patent No. 558,630. The recording device is connected with the counterpoise by a vertically-movable connection F in the nature of a bolt. It is carried by the counterpoise, and its weight forms a part of the weight of the counterpoise. It is moved downward by the counterpoise-latch lever b³ and upward by the counterpoise-latch spring b⁵ and also by a coil-spring surrounding it. (See Fig. 4.) The upper part f of the connection is contained in a guiding-sleeve f', and it is connected with the counterpoise-latch lever by a rock-shaft f², supported at f³, the arm f⁴ of which engages the upper end of the sliding connection and the arm f⁵ of the counterpoise-latch lever b³. The end of the last-named arm f⁵ has a slot f⁶, into which a pin f⁷, extending from the side of the counterpoise, projects and plays. The lower end of the sliding connection F has the tapering surfaces f⁸ and f⁹. The bolt or connection is represented as engaging the upper plate of the vertically-movable section c' of the record-

ing device, the said plate having a hole c^3 of the size of the main part of the bolt or connection.

Upon actuating the counterpoise-latch lever to disengage its registering-latch b^2 in order that the counterpoise may be slid upon the scale-beam to another position the connection or bolt F is moved downward and engages the section c' of the recording device, so that the movement of the counterpoise also causes the movement of the recording devices. When the counterpoise has been located in its new position and latched, its latching-lever returns to its highest position, thereby allowing the bolt or connection to be lifted by its spring to its highest position and to become practically disengaged from the recording devices, although its pointed end still remains in the hole c^3 in plate c^4 , thereby causing its inclined or tapering ends to remain in such relation to the recording devices that they may act as centering devices for them as the section c' is lifted to the type on the scale-beam and small counterpoise to print an impression of the weight.

It will be understood that the small counterpoise carries a short type-bar with inverted numerals, as in the case of my patents above referred to. If the recording devices are not in line with the particular numeral whose position the main counterpoise indicates, it is upon its upward movement centered in respect to said numeral by contact of one edge or other of the hole with one or the other of the inclined or tapering ends of the locking connection. The small counterpoise is at the same time centered to bring its numeral in line with the numeral of the main beam by means of a short pointed outwardly-extending spur or tooth e on the plate c^5 , which enters one of a series of registering-holes c^6 in the bottom of the counterpoise.

The printing-ribbon is carried by the reels D and D' , which are operated as described in my said Patent No. 558,630, but which are arranged with their axes lengthwise the recording device instead of crosswise it, as in said patent, and the ribbon extends from one reel over a small antifriction-roll d upon the plate c^4 forward to a small antifriction-roll d' on the plate c^5 , and then backward upon the same line over roll d^3 to the second reel. This brings over the platen c^6 the same ribbon, but in two thicknesses folded upon it to run in opposite directions, thereby providing two printing-sections, the upper of which is adapted to print upon the continuous recording-strip which extends from the reel H to the reel H' , and the lower of which is adapted to press upon a recording ticket or slip inserted over the plate c^4 upon the platen between the platen and the printing-section of the ribbon. The continuous recording-strip is fed as described in my said Patent No. 558,630.

65 The operation of the device is as follows: The tare having been determined, the main

counterpoise is moved upon the main scale-beam, as in ordinary weighing, its latch being held lifted from the notches, and a connection between the counterpoise and the recording device being established at the same time by the lifting of the latch, the counterpoise and recording devices are simultaneously moved. When the counterpoise has reached its balancing position, its latch is allowed to engage the proper notch, and by said engagement the connection between the counterpoise and the recording devices is established, so that the counterpoise is free to act as a counterpoise simply and without being hampered or restrained by the weight of the recording devices or any part thereof. The smaller counterpoise is then moved to establish the accurate balancing of the main counterpoise, and by so doing its type-bar is moved and the numeral which indicates the weight which it is set to brought in line with the numeral expressing the weight to which the main counterpoise is set. The upper section of the recording device is then moved upward and is centered and locked in relation to the main counterpoise, and it serves to center and lock the same counterpoise, and an impression by the numerals indicating the weight is printed upon the recording-strip and also upon a supplemental ticket or strip at the same time, if desired.

The recording-strip and the printing-ribbon are fed by the means described in my said patent; but any other suitable means may be employed for feeding them.

I prefer that the recording devices be incased in a casing which provides an opening for the insertion of the ticket or slip, but which covers the recording-strip and the recording devices, which case may be locked, if desired, so that access to the recording-strip may not be had by the weigher.

Having thus fully described my invention, I claim and desire to secure by Letters Patent of the United States—

1. The combination of the main scale-beam, its type, the counterpoise movable thereon, a stationary support below the same, a recording device movable upon said stationary support, the upper section of which is movable upward, and means for centering said upwardly-movable section in respect to the counterpoise, as and for the purposes set forth.

2. The combination in a scale of a movable counterpoise, a bar or short scale-beam, a movable small counterpoise on said bar or short beam having type and registering-holes and a recording device vertically movable in respect to said small counterpoise and having a registering-pin to enter one of the registering-holes therein.

3. The combination, in a recording-scale, of a scale-beam provided with type, a main counterpoise on said scale-beam, a bar or auxiliary scale-beam carried upon and movable with said counterpoise, a small counterpoise

provided with type carried on said bar or auxiliary scale-beam, recording devices vertically movable relative to said scale-beam and counterpoise, means independent of the type to automatically bring said recording devices

elevated, and independent means for alining said small counterpoise with respect to the recording devices.

JEREMIAH CAMPBELL.
